UNITED STATES PATENT OFFICE.

ERLE H. HAND, OF STAPLETON, NEW YORK.

RECORD CONTAINER AND EJECTOR.

Application filed November 29, 1921. Serial No. 518,568.

To all whom it may concern:

Be it known that I, ERLE H. HAND, a citizen of the United States, residing at Stapleton, county of Richmond, State of New York, have invented a new and useful Record Container and Ejector, of which the following is a specification.

In the commercial manufacture of record containers and ejectors, wherein the records are stowed vertically in compartments formed between closely related, vertical, parallel partitions, it is essential in order to obtain a maximum stowage capacity, that the partitions be thin and closely assembled to form the record holding compartments and there has heretofore been difficulty experienced from the warping of the partitions by reason of variations in temperature owing to climatic conditions, which warping is a very objectionable feature, as it interferes with the ready insertion and ejection of the records.

As the skeleton structure per se comprises broadly the assembly of these thin vertical partitions with top and bottom retaining devices for the upper and lower ends thereof, such a structure is necessarily somewhat fragile and trouble has been heretofore experienced in the handling, packing and shipping of these devices, since in the event of any rough usage, they are liable to become distorted or injured in packing, shipping or in transit.

Furthermore, in devices of this general character, wherein the bottoms of the record holding compartments are formed by ejector levers upon which the records roll, thin records are sometimes liable when their rear-most or stowed position to slip past the rear edge of the ejector lever, so that when the front end of the lever is depressed, the record will not be ejected but will stick in the rear of the apparatus.

To obviate the foregoing disadvantages, I have devised my present novel form of ejector, wherein I have produced a novel construction of outer protective framework, which encloses the skeleton and is composed of uprights, and horizontal members, which are in whole or in part duplicates and can be cheaply manufactured in quantities and whose juxtaposed contiguous ends are tied together by tongue and groove or dove-tailed connections, whereby an outer enclosing and supporting frame structure of great rigidity and durability is produced, which

affords the necessary protection to the skeleton composing the record holding compartments, so that the latter will not become distorted or injured in handling, packing, shipping, in transit or in use.

To prevent the objectional warping of the partitions, I have devised a novel construction of partition, which can be made out of paste-board, parchment, wood, wood fibre or any other suitable material and which is of novel contour, having a vertical front, upper and lower front tongues or attaching points, converging rear walls and a rear tongue, whereby the partitions have a three-point suspension, the points of suspension being at the front, top and bottom portions and at the rear of the partition on its horizontal median line, whereby said partitions forming the sides of the record holding compartments are so suspended, secured and braced, that there is no liability of their warping or buckling under any conditions.

In order to obviate the liability of the rear periphery of a record slipping past the rear portion of the ejector lever, when the front end of the lever is depressed, I have devised a novel construction of ejector lever of greater width at its rear portion behind its fulcrum than at its front, and which may be made of wood or stamped or pressed out of metal, whereby this trouble is obviated, particularly when this novel type of lever is collocated with my novel type of partition.

To the above ends my invention consists of the novel features of construction and advantage hereinafter described and more fully pointed out in the claims.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of the outer framework for enclosing and protecting the skeleton, showing one manner of constructing and assembling the same.

Figure 2 represents a vertical sectional view of the completed and assembled ejector

showing the position the records assume when in their rearmost or stowed position.

Figure 3 represents a front elevation of Figure 2.

5 Figure 4 represents a plan view of the partitions employed, showing the manner of producing the same.

10 Figure 5 represents a vertical sectional view of the lower portion of the ejector showing the position an ejector lever assumes after a record is ejected.

Figure 6 represents a perspective view of an ejector lever in detached position.

15 Figure 7 represents a section on line 7—7 Figure 2.

Figures 8 and 9 represent perspective views of modified forms of portions of the frame seen in Figure 1.

20 Figures 10, 11, 11^A and 12 represent perspective views of different forms of ejector levers.

Figure 13 represents a plan view of a partition adapted to be assembled with the rods and spacing strips.

25 Figure 14 represents a perspective view of the rear of an ejector partly assembled.

Figure 15 represents a front elevation of Figure 14.

30 Figure 16 represents a perspective view of another manner of assembling the ejector and partitions.

Figure 17 represents a plan view of a washer employed.

35 Figures 18 and 19 represent different means of supporting a triangular partition.

Figure 20 represents a perspective view of the lever seen in Figure 19.

Similar numerals of reference indicate corresponding parts.

40 Referring to the drawings:—

In carrying out my invention, I have (a) 45 standardized all the elements composing the outer frame-work, so that the cost of manufacture and assembling is reduced to a minimum, and (b) I also devised a novel structure and configuration of partition, wherein waste in production is eliminated, and, a partition produced having three points of suspension, whereby warping and buckling 50 thereof is prevented, and I am enabled to dispense with the expense and labor incident to the gluing operations heretofore employed, and (c) I have devised a novel ejector lever having increased lateral width at 55 its rear portion, whereby provision is made for ensuring that the rear portion of the lever and the kicker thereon will properly contact with the rear periphery of the record when said rear portion is elevated in the 60 act of ejecting a record, said levers being so collocated that there is no liability of a record slipping between or below the rear portions of the lever, the foregoing novel features being hereafter described in the order 65 named.

Referring first to Figure 1, 1 designates the frame-work which is composed of two end frames, which are duplicates. Each end frame comprises a front upright 2 having the top tongue 3 and the lower tongue 4. 70 The rear uprights 5 have a top tongue 6 and a bottom tongue 7 and the rear groove or seat 8. The horizontal end top brace 9 has the front groove 10, the rear groove 11 and the top transverse groove 12, both of the end top braces 9 being duplicates. The bottom horizontal end braces 13 are duplicates of each other and of the top braces 9 and each has the front groove 14, the rear groove 15 and the bottom transverse seat or 80 groove 16. When the frame is assembled, the tongues 3 and 4 are interlocked with the grooves 10 and 14. The tongues 6 and 7 are interlocked with the grooves 11 and 15.

The terminals 17 of the top strip 18 are 85 then seated in the grooves or seats 12, the terminals 19 of the bottom strip 20 are inserted in their seats 16, and the terminals 21 of the back strip 22 are seated in the seats 8, the juxtaposed contiguous tongues 90 and grooves of the above elements being if desired, when assembled, glued, pinned, doweled or otherwise secured together.

The top strip 18 has on its underside the parallel grooves 23, which are in vertical 95 alignment with the upper grooves 24 of the bottom strip 20, both of which grooves are also in alignment with the grooves 25 of the back strip 22, said grooves 23, 24 and 25 being readily cut in one operation by a 100 gang of saws. The frame-work having been assembled as above described, is now ready for the reception of the partitioning devices, which may be cut by a die from sheets of pasteboard or other material, as indicated 105 in Figure 4, so that there will be no waste. The contour of the partitions will be understood from Figures 2 and 3, said partitions being generally of triangular contour and having the front vertical wall 27 110 having the top tongue 28 and the bottom tongue 29. The rear walls 30 converge and terminate in the tongue 31, which is located on about the horizontal median line of the partition, so that when the partitions are 115 slid into place, the tongues 28, 29 and 31 engage respectively the grooves 23, 24 and 25, so that each partition has a three-point suspension, the rear point of suspension being about on the horizontal median line, whereby buckling or warping thereof under all 120 conditions is prevented.

The front edges 27 of the partitions may be stripped with tape, cloth or paper to enhance the front appearance of the device, 125 and the spaces between said partitions form record holding compartments 32 in which the records 33 and 34 of varying diameters are received.

The bottoms of the compartments 32 are 130

formed by the ejector levers 35, which may be made of wood or metal, the lever shown in Figures 2 to 6 being made of metal and comprising the front portion 36, and the rear portion 37, which has the upturned rear terminal or kicker 38.

39 designates a transverse hole for the fulcrum rod 40 which is located at the rear of the center of gravity of the lever, so that when a compartment is empty or a lever is unloaded, its front end will gravitate downwardly, thus serving as a signal or tell-tale to indicate the empty compartment in which to replace the record. The lever 35 has a longitudinally extending groove 39* therein, which serves both to stiffen and reinforce the lever and also as a guide track for the periphery of the contacting record. The front end of the lever is provided with the converging top and bottom faces 41 and 42, on which are suitable numbers or insignia, the object of the bottom bevelled face being to enable the user to ascertain the desired ejector lever, when the latter is above the level of his eyes.

The outer ends of the fulcrum rod 40, are secured or mounted in the bottom end braces 13, as indicated at 43, and it will be apparent from Figures 2 and 5 that the widened rear portion 37 of each ejector lever can oscillate freely out of contact with the rear of the partitions, while the front portion 36 of each lever is accurately guided between the bottom tongues 29 of the adjoining partitions. By the rearward prolongation of the partitions bounded by the converging walls 30 and the rear tongue 31, elongated guiding surfaces are formed for the entire diametric area of the record, and the location and manner of fastening the rear tongue 31 on about the horizontal median line of the partitions effectively prevents warping and buckling of the partitions and it will be evident that by cutting the partitions from a blank in the manner seen in Figure 4, waste is reduced to a minimum.

In Figures 8 and 9, I have indicated the end frames 44 and 45 and their adjuncts, which correspond to the parts 2, 5, 9 and 13 already described as being connected by dovetail joints 66 and as their construction and manner of assembling will be apparent, further detailed description is unnecessary.

In Figure 10 I have shown the ejector lever 46 as being made of wood, while the levers 47 and 48, seen in Figures 11 and 12 are different embodiments of the metal lever seen in Figure 6. In Figures 13 to 15, I have shown another manner of assembling the triangular ejector structure, having the front edge 27, and the top, bottom and rear tongues 28, 29 and 31 respectively, said tongues 28 as seen in Figure 13, having the

holes 49 therein, the tongue 29 having the holes 50 therein and the tongue 31 having the holes 51 therein, said holes being produced simultaneously with the punching of the partition, if desired.

In assembling the ejector to produce the structure seen in Figures 14 and 15, I employ pairs of duplicate tie rods 52, which may have the slotted heads 53, and the threaded ends 54 which are engaged by the nuts 55.

While all the tie rods are duplicates, I have designated the lower rod or rods as 52, the upper rods 56, and the rear rods 57, it being apparent, however, that if desired a single tie rod may be employed at the top, bottom and back of the partitions, and a single hole instead of the pairs of holes at the points 49, 50 and 51.

In order to space the partitions apart so as to form the record holding compartments, I employ the spacing strips or bars which are duplicates, but in order to designate their location, I have designated the top spacing strips as 58, the bottom spacing strips as 59, and the rear spacing strips as 60. These spacing strips, are collocated at the top, bottom and rear of the partitions, as indicated in Figure 14, and it will be apparent that by their use the partitions are effectively spaced so as to form the compartments 61 seen in Figure 15, which correspond to the record holding compartments 32 seen in Figure 3 already referred to.

Referring to Figure 14, the left hand ends of the tie rods 52 are supported in the bottom brace 62 and the left hand ends of the tie rods 56 are supported in the top horizontal brace 63, said braces being secured or dove-tailed to the vertical front and rear uprights 64 and 65 respectively.

I preferably unite the braces 62, 63, 64 and 65 by means of dove-tail joints as indicated at 66, thereby forming the rectangular end frame 67, which is constructed the same as the opposite or right end frame, 68, seen in Figure 14, whereby a very rigid and durable structure is produced.

In assembling the structure seen in Figure 14, I may first insert the tie rods 52, 56 and 57 through one of the frames, as the end frame 67. I next slip on the upper tie rods, a spacing strip 58 and on the lower tie rods a spacing strip 59 and on the rear tie rods, a spacing strip 60.

The partition is then placed upon the tie rods, and slid against the spacing strips after which another set of spacing strips is placed in position and then another partition, and so on.

When the partitions and spacing strips are assembled, the end frame 68 is slipped on the ends of the tie rods and the nuts 55 are then tightened, whereupon the re-

sultant device will be found to be very stiff, rigid and unyielding and the partitions will be held taut under all conditions, so that there will be no warping or buckling of the same. In the construction seen in Figure 14, the end frames 67 and 68 may be dispensed with if desired.

The ejector levers 35 are then positioned in the bottom of the compartments and the fulcrum rod 40 assembled or passed transversely through them and the device is then ready for use, the ejector levers forming the bottom of the various compartments and supporting the records during their insertion and ejection therefrom.

In Figure 14 I have shown at the left thereof, the manner of mounting a single lever, it being of course understood that the ejector levers are all positioned in the bottoms of the compartments 61, after the manner shown in Figures 2, 3, 5 and 7.

In Figure 16, I have shown another means for effecting the spacing of the partitions, which consists of the washers 69, which may be of any suitable material, such as metal, wood, fibre or the like.

It will of course be understood that in lieu of the employment of the construction of tie rods 52 having the heads 53, I may employ a single straight piece of wire cut off to the desired length and having both of its ends threaded instead of one end as seen in Figure 16.

In all of the embodiments of my invention, it will be apparent that the partitions have the generally triangular contour and three points of suspension will result in a partitioning device which will not warp or buckle, and which will be held taut under all conditions.

It will be of course understood that while I have shown in Figures 2, 3, 5, 6, 11, 11^A, 12 and 14, the employment of metal ejector levers, other levers may be employed if desired, and said levers and partitions may be constructed of any desired or suitable material.

In Figure 11, I have shown one manner of forming the blank from which the lever seen in Figure 11^A is constructed, said blank being designated as 70 and comprising the widened rear portion 71, the narrower front portion 72 having the tongue 73. The widened portion 71 has the terminal tongue 74 and the intermediate tongues 75. After the blank 70 seen in Figure 11 has been acted on by suitable dies, the structure seen in Figure 11^A is produced, it being apparent that the outer edges of the portions 71 are bent downwardly on the dotted lines, forming 71^A, while the edges of the portion 72 are also bent downwardly on the dotted line, forming 72^A. The tongue 73 is bent to form the converging terminals 41 and 42 seen in Figure 11^A and the right hand tongue

74 is bent to form the kicker 38 seen in Figure 11^A. The intermediate tongues 75 are bent under the body of the lever in order to stiffen and reinforce the same and appear after the lever is completed as indicated at 76.

It will be seen from the foregoing that the finished lever 11^A will be very rigid and durable by reason of the depending side walls formed by the pressing or stamping operation.

In Figure 18, I have shown the record holding compartments as being formed of triangular shaped partitions 77, said partitions having a single tie rod passing through their apices, the upper tie rod being designated as 78, the lower tie rod as 79 and the rear tie rod as 80, it being apparent that said partitions are spaced apart by means of the washers 69 seen in Figure 17.

In Figure 19, I have shown another form of triangular partition 81, which is assembled with the base of the triangle 82 standing horizontally at the upper portion of the ejector, the bridging space 83 of the triangle converging downwardly.

The record holding compartments are formed by means of the front upper tie rod 84, the rear tie rod 85 and the bottom rod 86, which serves as a fulcrum rod for the ejector levers 87, it being apparent that the bottom rod 86 serves to retain in proper position the lower apices of the triangular partitions with respect to each other and with respect to the ejector levers between them.

In Figure 20, I have shown on an enlarged scale the ejector lever 87, the same being provided with the side notches 88 to receive the lower apices of the triangular partitions.

It will be apparent that in the embodiments of my invention seen in Figures 18 and 19, I employ the same principle of three-point suspension, the advantages of which have already been explained, and I also somewhat reduce the expense of assembling, since I employ but a single tie rod or assembling member at the apices of the partitions.

Having thus described my invention, what I claim as new and desire to secure by Letters Patent is:

1. In a device of the character stated, record holding compartments having their walls formed by vertically disposed triangular partitions, means for securing said partitions in assembled position, and ejector levers fulcrumed at the lower portions of said compartments, the front portions of said levers being of uniform width, and the rear portions of said levers extending behind, the inclined bottom edges of said partitions being of greater width than said

front portions for the purpose of effecting a positive engagement with the lower rear periphery of a housed record when the front end of a lever is depressed to eject 5 said record.

2. In a device of the character stated, a compartment for a record container and ejector having its walls formed by partitions, provided with upper and lower 10 tongues, the rear top and bottom edges of said partitions converging rearwardly and meeting to form a rear tongue, fastening devices for said tongues and an ejector lever positioned in the bottom of said compartment and fulcrumed at a point at the 15 rear of its center of gravity and adapted to support records during their insertion and ejection, said lever being widened at the rear of its fulcrum.
3. In a device of the character stated, an inclosing framework for an ejector skeleton comprising two end frames composed of front and rear uprights, horizontal top and bottom braces for said uprights, tongue 20 and groove connections for the abutting portions of said braces and uprights, transverse connecting devices common to said end 25

frames, record holding compartments formed between said end frames, and record ejecting means in said compartments. 30

4. In a device of the character stated, a record holding compartment formed of a plurality of triangular partitions, means spacing said partitions apart and securing them in horizontal alignment with respect to 35 each other, a fulcrum rod located below said partition, an ejector lever mounted on said fulcrum rod, said lever being widened at its rear portion behind said fulcrum rod and being provided with recesses at the 40 point where said fulcrum rod passes through it, and an upwardly projecting rear kicker attached to said lever.

5. An ejector lever comprising a body having its fulcrum point located at the 45 rear of its center of gravity, its rear portion wider than its front portion, its front end having converging terminal walls, and a longitudinal groove in the top of said body.
